UNITED STATES PATENT OFFICE.

GEORGE E. TURNER, OF BUCYRUS, OHIO, ASSIGNOR TO STIRLING COMPANY, OF CHICAGO, ILLINOIS.

WATER-TUBE BOILER.

SPECIFICATION forming part of Letters Patent No. 752,630, dated February 16, 1904.

Application filed August 11, 1902. Serial No. 119,235. (No model.)

To all whom it may concern:

Be it known that I, GEORGE E. TURNER, a citizen of the United States, residing at Bucyrus, in the county of Crawford and State of Ohio, have invented certain new and useful Improvements in Water-Tube Boilers; and I do declare the following to be a clear, full, and exact description of the invention, such as will enable others skilled in the art to which it applies to make and use the same.

In the construction of water-tube steam-boilers one of the familiar difficulties encountered is in providing effective connections between the water-tubes and the steam-drums and the mud-drums. It is found in practice that the drums are weakened by the numerous holes cut in their walls to receive the ends of the water-tubes, and that owing to the thinness of the walls of the drums at these points it is difficult to form a satisfactory joint by expanding the ends of the tubes in place. To meet this difficulty, many complicated and expensive devices have been resorted to. It has been proposed by steam-boiler designers to thicken the metal of the drums at one side in a plane flat surface and to thus permit the use of straight tubes of uniform length; but in practice this has not been found feasible, for the reason that the drums are unduly weakened by a departure from the curved cross-section.

My invention relates to and its object is to provide cheap and simple means for overcoming the objection here indicated; also, to provide an arrangement of steam-drums, mud-drums, and water-tubes which will furnish a simple, effective, and durable, as well as an economical and convenient, water-tube steam-boiler. I attain these objects by means of the devices, construction, and arrangement of parts hereinafter described, and shown and illustrated in the single figure of the accompanying drawing, which is a vertical longitudinal sectional elevation of my boiler.

In the drawing, 1 and 2 are a pair of steam and water drums, the drum 1 being hereinafter designated as the "front" upper drum and 2 as the "rear" upper drum.

3 and 4 are mud-drums disposed below the drums 1 and 2. 3 will be hereinafter desig-

nated as the "front" mud-drum and 4 as the 50 "rear" mud-drum.

The front upper drum and the front mud-drum are connected by a series or bank of tubes 5. The rear upper drum and the rear mud-drum are connected by a series or bank 55 of tubes 6. The rear upper drum and the front mud-drum are connected by a series or bank of tubes 7. The steam-spaces of the two upper drums are connected by steam-pipes 8, and the water-spaces of these two drums are 60 connected by water-pipes 9. The two mud-drums are not directly connected with each other. This boiler thus arranged is provided with the usual feed water and steam pipes, steam-gages, and the like and is mounted 65 after the usual manner of this class of boilers in settings of masonry. The furnace is in front of the front bank of tubes 5, near its bottom. At the rear of the bank of tubes 5, extending from the front mud-drum upwardly nearly to the front upper drum, is a baffle-plate 10, which is interposed between the banks of tubes 5 and 7. Another baffle-plate 11 extends downwardly from the rear upper drum nearly to the rear mud-drum. 70

The course of the heated gases from the furnace is upwardly in front of the baffle-plate 10, thence downwardly between the baffle-plates 10 and 11, thence upwardly in the rear of baffle-plate 11, and out through the stack. 75 The general circulation of the water in my boiler is as follows: From the front mud-drum up through tubes 5 to the front upper drum, thence through tubes 9 to the rear upper drum, thence down through tubes 7 to the front mud-drum. In addition to this circulation there are secondary and independent currents up and down in the tubes 6 between the rear upper drum and the rear mud-drum. 80 85

The walls of the portions of the drums which receive the ends of the water-tubes are thickened longitudinally to a greater thickness than the remainder of the drum. The interior and exterior surfaces of the thickened portions are curved in the direction of the circumference 90 of the drums. It will be seen that the access of metal in the walls of the drums where numerous holes are bored to receive the tubes

greatly strengthens the drums at this point, provides for greater area of contact, and insures a stronger and tighter joint than is obtainable with thinner metal.

5 Having described my invention, what I claim, and desire to secure by Letters Patent, is—

1. A water-tube boiler comprising two elevated steam and water drums, a pipe connecting the steam-spaces of the two elevated steam and water drums, a pipe connecting the water-spaces of the two elevated steam and water drums, two lower mud-drums, a series of tubes connecting the front lower mud-drum with the front elevated steam and water drum, a series of tubes connecting the rear lower mud-drum with the rear elevated steam and water drum, and a row of tubes connecting the front lower mud-drum with the rear elevated steam and water drum, substantially as described.

2. A water-tube boiler comprising two elevated steam and water drums, a pipe connecting the steam-spaces of the two elevated steam and water drums, a pipe connecting the water-spaces of the two elevated steam and water drums, two lower mud-drums, a series of tubes connecting the front lower mud-drum with the front elevated steam and water drum, a series of tubes connecting the rear lower mud-drum with the rear elevated steam and water drum, a row of tubes connecting the front lower mud-drum with the rear elevated steam and water drum, and a row of tubes connecting the lower mud-drum and the rear elevated steam and water drum, substantially as described.

3. A water-tube boiler comprising two elevated steam and water drums, a pipe connecting the steam-spaces of the two elevated steam and water drums, a pipe connecting the water-spaces of the two elevated steam and water drums, two lower mud-drums, a series of tubes connecting the front lower mud-drum with the front elevated steam and water drum, a series of tubes connecting the rear lower mud-drum with the rear elevated steam and water drum, a row of tubes connecting the front lower mud-drum with the rear elevated steam and water drum, and a baffle-plate located between the series of tubes connecting the front lower mud-drum and the front elevated steam and water drum and the row of tubes connecting the front lower mud-drum with the rear elevated steam and water drum and extending upwardly from the front lower mud-drum, and a baffle-plate between the series of tubes and the row of tubes connecting the rear lower mud-drum and the rear elevated steam and water drum and extending downwardly from the rear elevated steam and water drum, substantially as described.

upwardly from the front lower mud-drum, substantially as described.

4. A water-tube boiler comprising two elevated steam and water drums, a pipe connecting the steam-spaces of the two elevated steam and water drums, two lower mud-drums, a series of tubes connecting the front lower mud-drum with the front elevated steam and water drum, a series of tubes connecting the rear lower mud-drum with the rear elevated steam and water drum, a row of tubes connecting the front lower mud-drum with the rear elevated steam and water drum, a row of tubes connecting the lower mud-drum and the rear elevated steam and water drum, and a baffle-plate between the series of tubes and the row of tubes connecting the rear lower mud-drum with the rear elevated steam and water drum, substantially as described.

5. A water-tube boiler comprising two elevated steam and water drums, a pipe connecting the steam-spaces of the two elevated steam and water drums, two lower mud-drums, a series of tubes connecting the front lower mud-drum with the front elevated steam and water drum, a series of tubes connecting the rear lower mud-drum with the rear elevated steam and water drum, a row of tubes connecting the front lower mud-drum with the rear elevated steam and water drum, a row of tubes connecting the lower mud-drum and the rear elevated steam and water drum, a baffle-plate between the series of tubes connecting the front lower mud-drum with the front elevated steam and water drum and the row of tubes connecting the front lower mud-drum with the rear elevated steam and water drum, a row of tubes connecting the lower mud-drum and the rear elevated steam and water drum, a baffle-plate between the series of tubes connecting the front lower mud-drum with the front elevated steam and water drum and the row of tubes connecting the front lower mud-drum with the rear elevated steam and water drum, a row of tubes connecting the lower mud-drum and the rear elevated steam and water drum, a baffle-plate between the series of tubes connecting the front lower mud-drum with the front elevated steam and water drum and the row of tubes connecting the front lower mud-drum with the rear elevated steam and water drum, and extending upwardly from the front lower mud-drum, and a baffle-plate between the series of tubes and the row of tubes connecting the rear lower mud-drum and the rear elevated steam and water drum and extending downwardly from the rear elevated steam and water drum, substantially as described.
